COMBINED COMPACT AND LIPSTICK HOLDER

Alfred F. Reilly, North Attleboro, Mass.

Application January 7, 1948, Serial No. 143,582

Term of patent 14 years

(Cl. D86—10)

To all whom it may concern:

Be it known that I, Alfred F. Reilly, a citizen of the United States, residing at North Attleboro, Massachusetts, have invented a new, original, and ornamental Design for a Combined Compact and Lipstick Holder, of which the following is a specification, reference being had to the accompanying drawing, forming part thereof.

In the accompanying drawing:

Fig. 1 is a front (and rear) elevation of a combined compact and lipstick holder, showing my new design;

Fig. 2 is a side elevational view of the same; and

Fig. 3 is a front elevation similar to Fig. 1, with the tassel parted to show the lipstick holder which is normally masked by the tassel.

I claim:

The ornamental design for a combined compact and lipstick holder, substantially as shown and described.

ALFRED F. REILLY.
